(57) **CLAIM**

The ornamental design for a handle for a knife, as shown and described.

DESCRIPTION

FIG. 1 is a perspective view of a handle for a knife showing my new design;

FIG. 2 is a front view thereof, the rear view being a mirror image of FIG. 2;

FIG. 3 is a top plan view thereof;

FIG. 4 is a bottom plan view thereof;

FIG. 5 is a right side elevational view thereof;

FIG. 6 is a left side elevational view thereof;

FIG. 7 is an enlarged cross-sectional view taken along line 7-7 of FIG. 2;

FIG. 8 is an enlarged cross-sectional view taken along line 8-8 of FIG. 2;

FIG. 9 is an enlarged cross-sectional view taken along line 9-9 of FIG. 2; and,

FIG. 10 is an enlarged cross-sectional view taken along line 10-10 of FIG. 2.

The broken lines shown in the drawings are for illustrative purposes only and form no part of the claimed design.
